CLAIM

The ornamental design for a sheer ease (rod holder), as shown and described.

DESCRIPTION

FIG. 1 is a front right side view of a curtain rod hook for a miniblind bracket, showing our new design; FIG. 2 is a side elevational view thereof with the opposite side being a mirror image; FIG. 3 is a rear elevational view thereof; and, FIG. 4 is a perspective view showing the article in use. The broken line showing of a bracket structure is for illustrative purposes only and forms no part of the claimed design.
